VAPOR GENERATOR

Ervin G. Bailey, Easton, Pa., assignor to The Babcock & Wilcox Company, Newark, N. J., a corporation of New Jersey

Application January 28, 1939, Serial No. 253,255

11 Claims. (Cl. 122—235)

The present invention relates in general to the construction and operation of vapor generating units, and more particularly to steam generating units designed for burning pulverized fuels having a range of ash fusion temperatures.

Coals that are used in pulverized form in such steam generating units as contemplated by this invention vary greatly both in physical characteristics and chemical analysis. While all coals contain ash to a greater or lesser degree, the percentage of ash, its chemical composition, and its physical characteristics while being essentially the same for coal from a given deposit or seam, vary very considerably between coals from different deposits. The ashes of all coals, however, in passing from the solid to the liquid phase pass through a transition zone defined by three temperature points, usually referred to as

1. Initial deformation temperature,
2. Softening temperature, and
3. Fluid temperature, which can be determined in the laboratory by well known standard methods, the ash residue from a slowly burned out coal sample being formed into a cone-shaped briquet, and the specific temperatures being determined in a muffle furnace. The initial deformation is that temperature at which the cone starts to distort and is indicative of when the lower fusing temperature particles of the heterogeneous mixture comprising the ash begin to soften and cement the higher fusing temperature particles. The softening temperature is that at which the cone has fused down to a spherical lump. The fluid temperature is that at which all ingredients of the ash become molten. The specific temperatures and the ranges between any two temperatures vary considerably with ashes of coals from different locations.

In burning pulverized coal in the furnaces of the steam generating units of my invention I desire to obtain the maximum practical thermal efficiency of the unit, or in other words, to utilize to the greatest possible extent the heat units in the coal being burned. This necessitates a consideration of many factors, but one of the most essential factors is the efficient and substantially complete combustion of the coal with the least practicable amount of excess air to attain these results. With these combustion conditions I naturally obtain the least weight of gases containing the maximum obtainable heat units from the coal, which results in high furnace temperatures. These furnace temperatures are in excess of the fluid temperatures of many of the individual constituents of the heterogeneous coal ashes, with

the result that upon combustion of the combustible material in the individual particles of pulverized coal the individual ash particles contained therein are exposed and raised in temperature, so that many of them become molten, and as the combustion of the combustible material proceeds small individual ash particles, some liquid and others plastic or solid, depending on their composition and fusion temperature, are liberated and carried away in the gases of combustion.

In the utilization of the combustion gases thus formed heat is abstracted therefrom, and from the solid particles of slag in suspension therein, either by radiation to a cooler surface bounding the gas flow, as, for example, water-cooled walls of a furnace, or by convection in passing over a bank of tubes at lower temperature, as, for example, a bank of boiler, superheater, economizer or air heater tubes, or by a combination of both radiation and convection heating. As the heat is abstracted from the gases the temperature of the gases and also the slag particles in suspension therein is decreased so that the slag passes through a range of temperature to below the initial deformation temperature at which point it is in solid condition.

Where the temperature of the gases and the slag particles in suspension therein is at or above the ash fluid temperature, the handling of such slag is relatively simple. The individual particles liberated from the coal and in suspension in the gases impact to some extent against each other but mostly against the walls of the furnace, and as the surfaces of these furnace walls, either because of their construction or due to a prior accumulation of slag thereon are maintained at a temperature also above the slag fluid temperature, the slag deposited thereon is maintained molten and runs down so that it can be satisfactorily disposed of, as, for example, in a slag tap furnace.

Similarly, when the slag particles in suspension in the gases have been cooled down to a temperature definitely below the initial deformation temperature of the ash, the handling is a relatively simple matter, as the slag is solid and "dry" and will not adhere to any cool surface with which it might come into contact, as, for example, a bank of tubes. Not only can these solid particles of slag be handled in a satisfactory manner, but the heat absorbing surface with which they and the carrying gases are in contact remains clean, so that the maximum heat transfer can be obtained.

In the range between these extremes of initial deformation and fluid temperatures, however, the slag is in a plastic or "sticky" condition and presents problems in the operation of a steam generating unit. Being "sticky" the slag will adhere to almost any surface with which it comes in contact, and furthermore, will build up and accumulate to extremely undesirable proportions even though there might be slow plastic flow within certain temperature ranges. This not only makes more difficult the problem of handling, but results in the formation of an insulating layer over whatever heat absorbing surface the slag is adhering to and materially reduces the absorption of heat. This condition is particularly serious if, for example, it is permitted to occur in a bank of tubes spaced relatively closely together, as there is a tendency for the slag accumulation on one tube to join with the slag accumulation on an adjoining tube and thereby not only effectively insulating those surfaces and reducing heat absorption, but also obstructing the passageway between the tubes to the passage of gas. As has been previously mentioned, the specific initial deformation and fluid temperatures of ash not only vary in ashes of different coals, but the ranges between these temperatures vary quite widely. As examples of these conditions, with specific coal ashes with which I have had experience, one coal has a relatively low initial deformation temperature of 2020 deg. F. with a relatively low fluid temperature of 2420 deg. F., the range being 400 deg. F. Another coal ash has a higher initial deformation temperature of 2350 deg. F., and a corresponding higher fluid temperature of 2750 deg. F., with an equivalent range of 400 deg. F. Still another coal ash has a relatively low initial deformation temperature of 2180 deg. F. and a relatively high fluid temperature of 2860 deg. F., with a wider range between these temperatures of 680 deg. F.

A further very important factor in connection with the physical characteristics of coal ash is that there is a selective separation of ash throughout the distance of travel of the gases. Coal ash is, by virtue of its formation, a heterogeneous mixture of individual constituents including oxides, carbonates, sulphides, sulphates, silicates, and the like of various metals, each with its own individual initial deformation and fluid temperatures, so that the temperature determinations made for any specific coal ash or slag sample are composite in nature. In the passage of the gases through a steam generating unit, the various individual ingredients of the heterogeneous mixture are not necessarily deposited at the same rate, as for example, a greater percentage of the larger and/or denser constituents is more likely to be deposited on the floor of the furnace and lower furnace walls early in the travel of the gases, than would be some of the other less dense ingredients, and this results in a modification of the composite temperature for the remaining ingredients in the slag at subsequent locations. In other words, while an analysis of an ash in a coal and determination of the initial deformation, softening and fluid temperatures give these composite figures for the complete heterogeneous mixture originally in the coal, the figures so determined are not necessarily representative of the specific slag conditions at any location in the travel of the gases beyond the furnace, but to the contrary will certainly not prevail, and composite temperatures other than

those of the original coal ash will prevail in various and different locations.

A steam generating unit of the type particularly applicable for the burning of pulverized coals having wide ranges of ash fusion temperatures is disclosed in my prior application Serial No. 88,285 filed July 1, 1936. One installation of the steam generating unit disclosed in said prior application has been successfully operated at a steam output of 225,000 lbs. of steam per hour with a steam pressure of 1260 lbs. per sq. in. and a steam temperature of 923 deg. F. burning a pulverized coal having an initial deformation temperature of 2180 deg. F., and an ash fluid temperature of 2860 deg. F. with a heat liberation in the primary furnace of 61,800 B. t. u. per cu. ft. per hour. The same unit has also been successfully operated at a steam output of 342,000 lbs. of steam per hour with a steam pressure of 1225 lbs. per sq. in. and a steam temperature of 910 deg. F., burning a pulverized coal having an initial deformation temperature of 2350 deg. F., and an ash fluid temperature of 2680 deg. F. with a heat liberation in the primary furnace of 98,000 B. t. u. per cu. ft. per hour. In the operation of this unit under both of these sets of conditions, the first set being indicative of medium rating, and the second set indicative of high rating with, incidentally, coals of different characteristics, the pulverized coal is burned in suspension in the primary furnace chamber by a turbulent type of burner at temperatures well above the fluid temperature of the ash, the adiabatic temperature being in the neighborhood of 3600 deg. F. and the temperature of the gases leaving the primary furnace ranging from 2920 deg. F. with medium rating to 2950 deg. F. with the high rating. In other words, the gases leaving the primary furnace chamber are at temperatures above the ash fluid temperature, thus permitting some of the ash that has been liberated from the coal in molten condition during combustion of the combustible material to be separated in the primary furnace and be removed in the liquid state. Combustion is substantially complete in the primary furnace.

In order to obtain steam temperatures of this order the superheating surface must receive gases at relatively high temperatures. The cost limitation of superheater construction, however, makes the use of small, closely spaced superheater tubes desirable. The distribution of steam and gas contact with the superheater elements must be substantially uniform to avoid overheating of these elements. These requirements necessitate the reduction of the high gas temperatures leaving the primary furnace to a temperature range at which the gases may safely contact with the superheater elements and yet be sufficiently high to obtain the desired heating effect. At the same time the slag particles in suspension must be removed or their temperature reduced below the slag initial deformation temperature before reaching the closely spaced superheater tubes in order to avoid slag in the plastic condition of the intermediate range between initial deformation and fluid temperatures contacting with and adhering to the superheater tubes, decreasing the heat transfer thereto, and accumulating to a point where the passage of gas therethrough is obstructed.

For these reasons on leaving the primary furnace chamber the hot gases and slag particles remaining in suspension therein are caused to

flow through an elongated narrow substantially unobstructed passage or "open pass" in which the gas and slag temperatures are reduced mainly by radiant heat absorption by the fluid cooled walls of the passage. With the first section of this passage vertically arranged for an upflow of the hot gases the slag separating out in this section, being still above the plastic point of the ash, flows down the walls thereof to the bottom of the passage, from which it is removed through a slag outlet along with the liquid slag separated out in the primary furnace itself. During the passage of the gases through the remaining or downflow section of the passage the gas temperature is further reduced through the plastic range between fluid and initial deformation temperatures. Such slag and gases that contact with the walls of this section of the pass being in a sticky or semi-sticky condition, may adhere to the walls and build up a spongy accumulation thereon. The construction of the walls in this portion of the passage however, is such as to present an essentially smooth surface so that a cleavage plane is provided between the surface and the slag thereon, with the result that there is a tendency for the accumulated slag to break away and fall to the bottom of this section of the passageway not only because of gravity acting on the accumulated mass itself, with the cleavage plane facilitating breaking away from the walls, but also due to the scrubbing action of the gases passing vertically downward at high velocity. Further than this, the surfaces of this portion of the passage are made readily accessible for cleaning, so that despite the fact that the slag in the gases is in the plastic range and tends to accumulate on the surfaces of the passageway, these surfaces can, nevertheless, be kept relatively clean, so that the heat is transferred from the gases and slag particles in suspension to the water tubes forming the passage walls or boundary, thus maintaining a high rate of heat transfer and conversely a rapid reduction in temperature both of the gases and the slag in suspension, so that as the gases pass from this portion of the passageway the slag particles remaining in suspension are cooled to a solid or dry state below the initial deformation temperature of the slag. This "open pass" section of the unit is suitably proportioned as to length, cross-section and effective heat absorbing surface so as to ensure a reduction in gas temperature through the desired temperature range and the suspended slag being in a solid condition below its initial deformation temperature when the gases enter the convection section of the unit containing the closely spaced superheater tubes.

The general object of my present invention is to provide an improved construction of steam generating unit of the type described, which is particularly characterized by an improved arrangement of the pressure parts, permitting of a substantial reduction in the number of drums and headers required, a higher rate of circulation in the steam generating section, greater accessibility of the surface for cleaning and renewal, a top or bottom support construction of the unit, and in general, improved operation at a substantially lower cost of construction and erection.

The various features of novelty which characterize my invention are pointed out with particularity in the claims annexed to and forming a part of this specification.

For a better understanding of the invention,

its operating advantages and specific objects attained by its use, reference should be had to the accompanying drawings and descriptive matter, in which I have illustrated and described preferred embodiments of my invention.

Of the drawings:

Fig. 1 is a graph showing the relationship between gas and ash temperatures throughout a steam generating unit extended to a point where the gases and slag particles in suspension therein are at a temperature below the initial deformation temperature of the slag;

Fig. 2 is a somewhat diagrammatic sectional elevation of a steam generating unit constructed in accordance with the invention;

Fig. 3 is a horizontal section taken on the line 3—3 of Fig. 2;

Fig. 4 is a horizontal section through one of the outer walls of the primary furnace;

Fig. 5 is a horizontal section through one of the partitions; and

Fig. 6 is a view similar to Fig. 2 illustrating a modified construction.

In Fig. 1 I have illustrated in graph form the relationship between gas and ash temperatures in operating the steam generating unit disclosed in my prior application Serial No. 88,285, filed July 1, 1936, at a moderate rating of 225,000 lb. of steam per hour at a steam pressure of 1260 lb. per sq. in. and a steam temperature of 923° F., so that the improvements forming the basis of my present invention can be better understood.

The abscissa of the graph indicates the area of the surface of the steam generating unit over which the gases pass, each division representing 500 sq. ft. At the top of the graph additional divisions are indicated dividing this surface into the primary furnace, first open pass, second open pass and cavity below superheater—the superheater being the first bank of convection heated tubes in the unit. From this graph it will be observed that the primary furnace, in the walls and roof, contains approximately 1800 sq. ft. of surface exposed to the gases, the first open pass 1100 sq. ft., and so on. The ordinate of the graph indicates temperatures from 1600° F. to 3100° F., each division representing 100° F.

On the zero ordinate are indicated the initial deformation, softening and fluid temperatures for the ash in the coal of 2180° F., 2250° F., and 2860° F. respectively, these temperatures being determined from a laboratory sample of the coal ash in the manner previously described. Corresponding temperatures determined for slag samples taken from various locations in the unit with respect to gas travel are also indicated, and lines drawn joining the equivalent temperatures, and it will be noted, as previously described, that these temperatures are not consistent but vary due to the selective separation of the various amounts of the individual constituents of the total heterogeneous mixture. The shaded area between the lines of initial deformation temperatures and fluid temperatures so drawn represents the varying range of plastic or "stickiness" temperatures of the slag at various locations in the steam generating unit.

In the zone indicating the primary furnace the adiabatic temperature, which will be in the neighborhood of 3600° F. is not shown, but the temperature of the gases leaving the primary furnace as determined by optical pyrometer is 2920° F., or above the ash fluid point. It is desirable to maintain this temperature in the primary furnace, not only to facilitate the removal

of some of the slag separated in molten form, but also to insure substantially complete combustion, and the water-cooled walls of the furnace are so constructed, as for example, employing partial stud tubes with refractory, as shown in Fig. 4, to insure this condition. In the first and second open passes the rapidly decreasing temperature of gases as determined by optical pyrometer and high velocity thermocouple is clearly shown, as is also the fact that the gas temperature is definitely below the initial deformation temperature before leaving the second open pass and entering the cavity below the superheater, so that the slag particles carried in the gases are definitely cooled to a solid condition as they contact with the first bank of tubes, or superheater, located above the cavity.

Referring to Figs. 2 to 5 the steam generating unit illustrated has its setting divided into a primary furnace chamber 10, a laterally spaced convection section 11 connected thereto by an intervening substantially unobstructed vertically elongated passage comprising upflow and downflow sections or "open passes" 12 and 13 respectively. The furnace chamber 10 is preferably of rectangular horizontal cross-section and defined by a front wall 15, opposite side walls 16, inclined roof 17, and floor 18. The furnace chamber is separated from the upflow passage section 12 except at its lower rear side by a partition wall 20 extending downwardly from the rear end of the furnace roof 17. The upflow and downflow passage sections are separated except at their upper ends by a partition wall 21 extending upwardly from the bottom of the setting. The downflow passage section 13 and convection section 11 are also separated except at their lower ends by a partition wall 22 extending downwardly from the top of the setting. The rear side of the convection section is formed by a panel wall 23 and the tops of the passages closed by a roof 24. The unit is advantageously of uniform width throughout, as shown in Fig. 3. With this division of the setting, the heating gases leaving through the lower rear side of the furnace chamber 10 flow upwardly through the passage 12, downwardly through the passage 13, and upwardly through the convection section 11, the upper end of which is connected to an induced draft fan (not shown).

In accordance with my invention the furnace chamber is made relatively narrow longitudinally of the setting, and the roof 17 constructed with one or more burner ports 25 extending transversely of the portion of the roof closely adjacent to the front wall 15. A combustion air box 26 receiving a supply of air from a forced draft fan (not shown) opens to the burner port 25. A plurality of pulverized coal burners 27 of a suitable turbulent type, such as shown in U. S. Patent 2,055,722, are mounted in the air box 26 so as to discharge streams of primary air and pulverized coal in suspension downwardly through corresponding burner ports into the furnace chamber 10. The narrow formation of the primary furnace and the described arrangement of the fuel burners relative to the furnace front wall and gas outlet results in an effective use of substantially the entire volume of the primary furnace. The entering fuel rapidly ignites and flows downwardly in a stream which tends to hug the front wall 15 during its downward travel, the gases flowing toward the gas outlet below the lower end of the partition wall 20. The primary furnace chamber 10 is entirely fluid cooled

as hereinafter described to permit its walls to withstand the maintenance therein of a normal mean temperature above the ash fluid temperature. The molten slag particles separating out in the primary furnace deposit on the roof, walls and floor thereof in a fluid condition and are removed through one or more slag discharge openings 28 located in the partition 21 slightly above the floor level in the primary furnace and passage section 12. The slag flowing through the slag outlet or outlets 28 drops into a water filled ash hopper 42 below the down pass 13.

The vertically arranged open passage sections 12 and 13 subsequent to the furnace in the direction of gas flow are made relatively narrow longitudinally of the setting, but are of such height that the combined distance of gas travel through them in series, together with the degree of cooling obtained by the specific construction of fluid cooled walls employed, is such as to ensure the gases entering the first open pass 12 from the primary furnace chamber 10 having slag particles in suspension and being at a temperature above the plastic range are cooled by the time they are discharged from the bottom of the second open pass 13 to a temperature at which the slag particles still remaining in suspension are below their plastic or "sticky" temperature. On entering the first upward flow open pass 12, the slag particles, being still above their fluid temperature, will adhere to the walls of the passage and will flow downwardly thereon to the floor 18 which is common to the primary furnace 10 and pass 12, and thence be discharged 35 with the molten slag separated in the primary furnace through the slag discharge opening 28.

On passing from the top of the pass 12 into the second downward flow open pass 13, the slag particles in the gases are at such a temperature 40 as to be in the lower portion of the plastic or "sticky" range between initial deformation and fluid temperature. The tubes in the screen between the first and second open passes are spread apart in the screen formation a sufficient distance so that such slag as might accumulate on them will not do so to an extent that will unduly restrict the gas flow area. The boundary walls of this second open pass are constructed in such a manner as to present cool and essentially 45 smooth surfaces to the flow of gases, as the sticky nature of the slag is such as to necessarily result in the slag adhering to and accumulating on these surfaces, and the smoothness of them provides a natural cleavage plane that enhances the 50 removal of the accumulations by their own weight. Furthermore, the gas flow in a downward direction facilitates and assists the removal of slag from the walls depositing it in the dry ash removal chamber immediately beneath this 55 second passage and the convection section, from which the slag is also removed in the solid and dry state. Both of the open passes are unobstructed by tube banks or the like, so that such 60 slag accumulations that occur must necessarily be upon the passage walls from which they can be readily removed, and there is no tendency toward obstructing the gas flow. Furthermore, the vertical positioning of these open passes is most conducive to the removal of slag separated 65 therein—in the first open pass in the molten state and in the second open pass in a solid or spongy state. The walls of both passes are susceptible to the application of cleaning means such as steam blowers or the like, to facilitate 70 and expedite the removal of slag accumulations 75

therefrom should this prove necessary, and in so doing the removal of the insulating layer of slag improves the heat transfer conditions and insures that the heat absorbed by the walls from the gases will be sufficient to result in the desired temperature conditions leaving the second open pass and entering the closely spaced convection tube banks.

The steam generating surface of the unit is mainly confined to the primary furnace chamber and the open pass with the heat absorbing elements mainly heated by radiation and vertically disposed as far as is possible, and all drums, headers and downcomer connections located out of the path of the heating gases. As shown, a horizontally elongated elevated steam and water drum 30 extends transversely of the unit directly above the partition wall 20 and above the level of the roof 24. The drum 30 is supported from the superjacent steel work by U-shaped straps 31. A horizontally elongated water drum 32 extends transversely of the unit below the upflow pass 12.

The steam generating surface consists substantially entirely of tubes heated mainly by radiation and located in the portion of the setting in front of the convection section 11. The steam generating tubes include a row of tubes 33 extending from the drum 32 along the floor 18, front wall 15, roof 17, and front wall of the upflow section 12, to the drum 30, and supported from the underside of the drum 30 by hanger rods 33^a. A second row of tubes 34 extends from the drum 32 across the lower end of the upflow passage section 12, along the partition 20 and front wall of the passage 12 to the drum 30. The inclined tube portions 34^a extending across the lower portion of the upflow passage are bent and spaced to form an inclined fluid cooled screen extending from the furnace floor to the lower end of the partition 20. The tube portions 34^a and the superjacent tube portions forming the partition wall 20 are studded and covered with refractory to the extent desired for most efficient operation of the unit. The upper portions 34^b of most of the tubes 34 are bent rearwardly across the upper part of the passage section 12 to facilitate their connection into the opposite side of the drum 30. A third row of generating tubes 35 extends vertically from the drum 32 along the partition wall 21, with the tube portions 35^a above the upper end of the partition wall bent and arranged to form a screen between the upflow and downflow passages 12 and 13 respectively. The tubes 35 are also provided with metallic studs and refractory material, as shown in Fig. 5, to define the partition wall 21. The partition wall is continued downwardly at the rear side of the drum 32 to the front wall of the ash hopper 42 below the downflow passage 13. A fourth row of tubes 36 extends upwardly from a header 37 along the inclined lower portion of the wall 23, across the lower end of the convection section, along the partition wall 22 and the roof 24 to the drum 30. The lower inclined portions of the tubes 36 are block-covered to form an inclined hopper flue terminating at the ash pit 42. The portions 36^a of the tubes 36 extending across the lower end of the upflow convection section are bent and spaced to form an inclined screen across the lower end of the convection section between the rear wall 23 and the lower end of the partition wall 22. The portions of the tubes 36 above the screen are provided with stud extensions and re-

fractory material, as shown in Fig. 5, to define the partition wall 22. The side walls of the furnace chamber 10 are each defined by a row of partially studded tubes 40 extending between horizontally arranged upper and lower headers 38 and 39 respectively. The side walls of the passage section 12 and 13 are defined by similar tubes 40^a extending between upper headers 41 adjacent the drum 30 and the headers 39. Tubes 10 43 defining opposite side walls of the convection section extend between the headers 39 and upper headers 44. The headers 38, 41 and 44 are connected to the upper drum 30 by riser tubes 45 which are hung from the superjacent steelwork 15 and in turn top support the side walls of the unit.

As shown, the drums 30 and 32 and headers 37, 38, 39, 41 and 44 are located out of the path of the heating gases. The fluid circulation 20 through the described generating elements is enhanced by the elevated position of the drum 30 and the external location of the various supply connections to the generating elements. As shown in Fig. 3, the drums 30 and 32 are connected by large standpipes 46 arranged at the outer side of the side walls 16. The tube connections to the drum 30 are preferably arranged along opposite sides of the drum, whereby the water in the bottom of the drum, to which the standpipes 46 open, will be relatively quiescent. The headers 39 are supplied from the standpipes 46 by tubes 47, the header 37 by external tubes 48, and the drum 32 by tubes 49.

The described construction is adapted for a higher heat liberation per front foot of furnace than the unit disclosed in my said prior application, so that the temperature in the primary furnace will be correspondingly higher. The final gas temperature entering the convection section must be approximately the same, however, and in the present construction the open passes are made considerably higher to insure a greater heat absorption in those sections of the unit. The present construction avoids any possibility of the lower end of the downflow passage becoming plugged by slag accumulations deposited from the walls of the passage, by arranging the tube screen 36^a across the entrance to the convection section, and thus leaving a free area from the downflow passage to the ash hopper formed below both the downflow passage and convection section. The relatively large fluid cooled cavity resulting in this portion of the unit further reduces the gas temperature, and affords an ample gas turning space in which suspended slag particles can separate and the gases more uniformly enter the convection section. The tube screen 36^a forms the final cooling zone before the gases enter the convection section.

The convection section of the unit is utilized solely for the location of the auxiliary heating surface of the unit. As shown, the entering heating gases first contact with a steam superheater consisting of vertically spaced serially connected tube sections 51 extending between inlet and outlet headers 52 and 53 respectively arranged externally of the rear wall 23. Adjacent tubes in the lowermost superheater section are arranged in nested rows to permit a greater transverse spacing between adjacent tube coils in the superjacent superheater sections. The superheater tube coils are supported at their inner ends from the partition wall tubes 36 in a well known manner and at their outer ends from

a cross-beam 54 through the header 52 and tube engaging elements.

A plurality of vertically spaced serially connected downflow economizer sections 60 are arranged in the convection section above the superheater sections. The economizer tube coils are also supported at their inner ends by the tubes 36 and at their outer ends from the vertical portions of the superheater tubes extending along the rear wall. A by-pass passage 10 containing 10 additional economizer surface 11 is arranged along one side of the convection section to permit regulation of the superheater temperature, as described in my said prior application. The panelled construction of the wall 23 and the absence of downcomer tubes or other heat absorbing tubes along that wall facilitates the inspection, repair and renewal of the auxiliary heating surface in the convection section.

The modified steam generator construction illustrated in Fig. 6 is particularly designed for the high capacity generation of steam at high pressures and steam temperatures of about 950° F. In units of this type, provisions may advantageously be incorporated for reheating the steam after a predetermined passage through an associated turbine. In the Fig. 6 unit, the heat absorbing surface defining the side walls of the downflow passage section 13 and the partition wall 22 is employed as a steam reheat. As shown, the steam to be reheated is supplied to the hopper header 37', and flows through the tubes 36' along the hopper wall, through the screen tubes 36^a and partition wall 22 to an upper header 80. The reheated steam is then passed to side wall headers 41', from which it flows downwardly through the side wall tubes 40' to outlet headers 42'.

While in accordance with the provisions of the statutes I have illustrated and described herein the preferred forms of the invention now known to me, those skilled in the art will understand that changes may be made in the form of the apparatus disclosed without departing from the spirit of the invention covered by my claims, and that certain features of my invention may sometimes be used to advantage without a corresponding use of other features. While the constructions illustrated are particularly designed for and especially useful for burning slag-forming pulverized coal, it is apparent that other fluid fuels, such as oil and gas, can be used therein.

I claim:

1. A steam generator comprising a setting including a furnace chamber and a convection section spaced laterally of and connected to the furnace chamber by a substantially unobstructed vertically elongated connecting passage arranged between said furnace chamber and convection section, means for burning fuel in suspension in said furnace chamber, a relatively large diameter main steam and water drum arranged at the furnace chamber side of said convection section, the steam generating surface of the steam generator consisting mainly of rows of vertically disposed tubes defining walls of said furnace chamber and connecting passage and receiving heat mainly by radiation, downcomer conduit means confined to the furnace chamber side of said convection section arranged to supply water from said drum to all of said radiantly heated tubes, and a bank of horizontally arranged steam superheating tubes extending across the path 15 of the gases flowing through said convection sec-

tion and connected to receive steam directly from said drum.

2. A steam generator comprising a setting including a furnace chamber and a convection section arranged laterally of and connected to the furnace chamber by an inverted U-shaped substantially unobstructed connecting passage, means for burning fuel in suspension in said furnace chamber, a relatively large diameter main steam and water drum arranged above said furnace chamber and laterally of said convection section, steam generating surface consisting mainly of rows of vertically disposed radiantly heated tubes defining walls of said furnace chamber and connecting passage and discharging to said drum, downcomer conduit means confined to the furnace chamber side of said convection section arranged to supply water from said drum to all of said radiantly heated tubes, and a bank of steam superheating tubes extending across the path of the gases flowing through said convection section and connected to receive steam directly from said drum.

3. A steam generator comprising a setting including a furnace chamber and a convection section spaced laterally from the furnace chamber, a substantially unobstructed connecting passage between and connected to said furnace chamber and convection section, means for burning fuel in suspension in said furnace chamber, an upper steam and water drum arranged at the furnace chamber side of said convection section and externally of said connecting passage, a lower water drum arranged at the furnace chamber side of said convection section, the steam generating surface of the steam generator being connected to said upper and lower drums and consisting mainly of rows of vertically disposed radiantly heated tubes defining walls of said furnace chamber and connecting passage, conduit means confined to the furnace chamber side of said convection section for supplying water from said upper drum to all of said radiantly heated tubes, and a bank of horizontally arranged fluid heating tubes in the path of the gases flowing through said convection section.

4. A steam generator comprising a setting including a furnace chamber and a convection section spaced laterally from the furnace chamber, a substantially unobstructed connecting passage having its opposite ends connected to said furnace chamber and convection section respectively, means for introducing a downwardly directed stream of slag-forming pulverized fuel into said furnace chamber and burning the same in suspension therein at a normal mean furnace chamber temperature above the fuel ash-fusion temperature, a fluid cooled slag-impervious floor for said furnace chamber, an outlet for molten slag in the lower part of said furnace chamber, an upper horizontally elongated main steam and water drum arranged at the furnace chamber side of said convection section, the steam generating surface of the steam generator discharging to said upper drum and consisting mainly of rows of vertically disposed radiantly heated tubes defining walls of said furnace chamber and connecting passage, conduit means confined to the furnace chamber side of said convection section for supplying water from said upper drum to all of said radiantly heated tubes, and a bank of steam superheating tubes in the path of the gases flowing through said convection section and connected to receive steam directly from said drum.

5. A steam generator comprising a setting including a furnace chamber and a convection section spaced laterally from the furnace chamber, an inverted U-shaped substantially unobstructed connecting passage having upflow and downflow sections with their lower ends connected to the lower portions of said furnace chamber and convection section respectively, means for burning pulverized fuel in suspension in said furnace chamber at a normal mean temperature therein above the fuel ash fusion temperature, an upper steam and water drum, a lower water drum, steam generating surface connected to said upper and lower drums and consisting mainly of rows of vertically disposed radiantly heated tubes defining walls of said furnace chamber and connecting passage, conduit means for supplying water from said upper drum to said radiantly heated tubes, a bank of fluid heating tubes in the path of the gases flowing through said convection section, means forming an ash pit below said downflow passage section, and an outlet for the passage of molten slag separated in said furnace chamber into said downflow passage section and ash pit.

6. A steam generator comprising a setting including a furnace chamber and a convection section spaced laterally from the furnace chamber, an inverted U-shaped substantially unobstructed connecting passage having vertically elongated upflow and downflow sections extending a substantial distance above the top of said furnace chamber with their lower ends connected to the lower portions of said furnace chamber and convection section respectively, means for introducing a downwardly directed stream of slag-forming pulverized fuel into said furnace chamber and burning the same in suspension therein at a normal mean furnace chamber temperature above the fuel ash-fusion temperature, an outlet for molten slag in the lower part of said furnace chamber, an upper steam and water drum arranged at the furnace chamber side of said convection section and externally of said connecting passage, a lower water drum arranged at the furnace chamber side of said convection section, steam generating surface connected to said upper and lower drums and consisting substantially only of rows of vertically disposed radiantly heated tubes defining walls of said furnace chamber, connecting passage and convection section, means for top supporting said drums and connected tubes, conduit means combined to the furnace chamber side of said convection section and connected to said steam and water drum and forming water supply connections to all of said radiantly heated tubes, and a bank of fluid heating tubes in the path of the gases flowing upwardly through said convection section.

7. A steam generator comprising a setting including a furnace chamber and a convection section spaced laterally from the furnace chamber, an inverted U-shaped substantially unobstructed connecting passage having upflow and downflow sections with their lower ends connected to the lower portions of said furnace chamber and convection section respectively, means for burning fuel in suspension in said furnace chamber, an upper horizontally elongated main steam and water drum arranged laterally of said convection section and externally of said connecting passage, a lower horizontally elongated water drum arranged at the furnace chamber side of said convection section, steam generating surface discharging to said upper drum and consisting

mainly of vertically disposed tubes heated mainly by radiation arranged at the furnace chamber side of said convection section, said steam generating tubes including a row of tubes defining the front wall and roof of said furnace chamber, a second row of tubes defining a partition wall between said furnace chamber and upflow passage section, and a third row of tubes defining a partition wall between said upflow and downflow passage sections, conduit means at the furnace chamber side of said convection section for supplying water from said upper drum to all of said radiantly heated tubes, and a bank of fluid heating tubes in the path of the gases flowing upwardly through said convection section.

8. A steam generator comprising a setting including a furnace chamber and a convection section spaced laterally from the furnace chamber, an inverted U-shaped substantially unobstructed connecting passage having upflow and downflow sections with their lower ends connected to the lower portions of said furnace chamber and convection section respectively, means for burning fuel in said furnace chamber, an upper steam and water drum arranged laterally of said convection section, steam generating surface discharging to said upper drum and consisting mainly of vertically disposed tubes heated mainly by radiation and defining walls of said furnace chamber and connecting passage, means forming an ash separating chamber below said downflow passage section and convection section and, having an unobstructed connection with said downflow passage section, and a bank of fluid heating tubes extending across the path of the gases flowing upwardly through said convection section.

9. A steam generator comprising a setting including a furnace chamber and a convection section spaced laterally from the furnace chamber, an inverted U-shaped substantially unobstructed vertically elongated connecting passage having upflow and downflow sections with their lower ends connected to the lower portions of said furnace chamber and convection section respectively, means for burning fuel in suspension in said furnace chamber, an upper horizontally elongated steam and water drum arranged laterally of said convection section, a lower water drum arranged at the furnace chamber side of said convection section and externally of and below said connecting passage, steam generating surface discharging to said upper drum and consisting mainly of vertically disposed tubes heated mainly by radiation arranged at the furnace chamber side of said convection section, said steam generating tubes including a row of tubes defining the front wall and roof of said furnace chamber, a second row of tubes defining a partition wall between said furnace chamber and upflow passage section, a third row of tubes defining a partition wall between said upflow and downflow passage sections, and a fourth row of tubes defining the rear wall of said downflow passage section, conduit means confined to the furnace chamber side of said convection section arranged to supply water to all of said tube rows, and a bank of fluid heating tubes in the path of the gases flowing upwardly through said convection section.

10. A steam generator comprising a setting including a furnace chamber and a convection section spaced laterally from the furnace chamber, an inverted U-shaped substantially unobstructed vertically elongated connecting passage having

upflow and downflow sections with their lower ends connected to the lower portions of said furnace chamber and convection section respectively, means for introducing a downwardly directed stream of pulverized fuel into said furnace chamber and burning the same in suspension therein, an external horizontally elongated steam and water drum arranged at the furnace chamber side of said convection section, and steam generating surface discharging to said steam and water drum and consisting mainly of vertically disposed tubes heated mainly by radiation arranged at the furnace chamber side of said convection section, said steam generating tubes including a row of tubes defining the front wall and roof of said furnace chamber, a second row of tubes defining a partition wall between said furnace chamber and upflow passage section, a third row of tubes defining a partition wall between said upflow and downflow passage sections, and a fourth row of tubes defining the rear wall of said downflow passage section, conduit means confined to the furnace chamber side of said convection section arranged to supply water from said drum to all of said tube rows, means forming an ash separating chamber below said downflow passage section and convection section and having an unobstructed connection with said down-

flow passage section and an inclined wall cooled by said fourth row of tubes, and a horizontally arranged bank of fluid heating tubes in the path of the gases flowing upwardly through said convection section.

11. A steam generator comprising a setting including a furnace chamber and a convection section spaced laterally from the furnace chamber, an inverted U-shaped substantially unobstructed connecting passage having upflow and downflow sections with their lower ends connected to the lower portions of said furnace chamber and convection section respectively, means for burning fuel in suspension in said furnace chamber, an upper steam and water drum arranged at the furnace chamber side of said convection section, steam generating surface directly connected to said upper and lower drums and consisting of vertically disposed tubes heated mainly by radiation arranged at the furnace chamber side of said convection section and defining walls of said furnace chamber and connecting passage, a bank of steam superheating tubes in the path of the gases flowing upwardly through said convection section, and steam reheating surface including rows of tubes defining the rear and side walls of said downflow passage section.

ERVIN G. BAILEY.

CERTIFICATE OF CORRECTION.

Patent No. 2,268,560.

January 6, 1942.

ERVIN G. BAILEY.

It is hereby certified that error appears in the printed specification of the above numbered patent requiring correction as follows: Page 6, second column, line 72, claim 4, before "steam" insert --horizontally arranged--; page 7, first column, line 53, claim 6, for "combined" read --confined--; and that the said Letters Patent should be read with this correction therein that the same may conform to the record of the case in the Patent Office.

Signed and sealed this 1st day of September, A. D. 1942.

Henry Van Arsdale,
Acting Commissioner of Patents.
